[57] CLAIM

The ornamental design for a channel lock valve cover, as shown and described.

DESCRIPTION

FIG. 1 is a diagrammatic perspective view of the channel lock valve cover in full lines with a gasket shown in broken lines representing environmental association matter being for illustrative purposes only and forming no part of the claimed invention.

FIG. 2 is a diagrammatic perspective view of the channel lock valve cover.

FIG. 3 is a front elevational view thereof, the rear elevational view being a mirror image of the front view.

FIG. 4 is a top plan view thereof;

FIG. 5 is a bottom plan view thereof.

FIG. 6 is a right side elevational view of the channel lock valve cover, the left side elevational view being a mirror image of the right side view.
